UNITED STATES PATENT OFFICE.

HENRY HEESE, OF JERSEY CITY, NEW JERSEY.

DETACHABLE CONNECTION FOR THE CABLES OF LIGHTNING-ARRESTER SYSTEMS.

Application filed January 26, 1925. Serial No. 4,877.

This invention relates to improvements in sectional clamps for cables and is more particularly adapted to a detachable connection for use in conjunction with the cables or 5 wires of a lightning arrester such as is embodied in my copending application.

One of the important objects of the present invention is to provide a detachable connection which is of such construction as to 10 enable the same to be readily assembled or disassembled, the simplicity thereof enabling considerable time and labor to be saved in its use.

A further object is to provide a detachable connection of the above mentioned character, which will at all times be positive and efficient in carrying out the purposes for 15 which it is designated, the same being further simple in construction, inexpensive, 20 strong and durable and further well adapted for the purposes for which it is designated.

Other objects and advantages of this invention will become apparent during the course of the following description.

25 In the accompanying drawings forming a part of this specification, and in which like numerals designate like parts throughout the same:

Figure 1 is a side elevation of the detachable connection associated with the adjacent ends of the elongated vertically extending wire and the ground wire.

Figures 2 and 3 are elevational views of the sections of said last mentioned connection, and

Figure 4 is a detail perspective view of the wire securing means associated with said detachable connection.

In the drawings, wherein for the purpose of illustration is shown the preferred embodiment of the invention, there is shown a detachable connection designated generally by the numeral 1, the same providing a means for connecting the adjacent ends of 40 the wire extending along the outer wall of the chimney and the ground wire. The detachable connection 1 comprises the complementary inner and outer sections 2 and 3 respectively. The intermediate portion of 45 each of these sections is enlarged as illustrated at 4. A pair of cooperating channels 5 and 6 are arranged in the inner opposed faces of the complementary sections 2 and 3, the same extending from the lower end 50 to one side of the intermediate portion of the connection for receiving the upper end

of the ground wire A. A similar pair of cooperating channels 7 and 8 are arranged in the upper portions of the inner faces of the complementary sections, the construction 60 thereof being clearly illustrated in Figures 2 and 3. The cooperating grooves 7 and 8 respectively provide an opening for receiving the lower end of the wire B which extends downwardly along the outer wall of 65 the chimney.

The lower end of the inner section 2, is provided with the laterally extending ears 9, the same being provided with internally threaded openings 10 for registry with the 70 openings 11 provided in the laterally extending ears 12 formed on the lower end of the complementary outer section 3 whereby the fastening screws 13 afford a means for securing the lower ends of the complementary 75 sections together. The upper end of the inner section 2 is provided with a pair of laterally extending ears 14, the latter being provided with the openings 15 for receiving the tongues 16 formed on the upper end of 80 the outer section 3 whereby an interlocking and interfitting connection between the upper ends of the complementary sections is provided.

For the purpose of securing the portions 85 of the wires which are disposed in the intermediate portions of the sections of the connection 1, I provide the wire engaging member 17 which is removably disposed in the opening 18 provided therefor in the intermediate portion of the outer section 3, the opening 18 being arranged diagonally and communicating with the cooperating channels of the section. This wire engaging member comprises a substantially block-like 90 body 24 that is of such size as to fit within the opening 18 formed in the outer section 3. A plate-like member 25 is formed on the upper or outer face of this block and is of greater size than the block, and the inner 95 face of this plate like portion will engage the outer face of the outer section around the opening 18. The bottom face of the rectangular block 24 is cut away at each end as illustrated at 26 and a transversely extending tooth 27 is formed in each of the cut away portions. These teeth bite into the ends of the respective wires or cable that are arranged in the cooperating channels provided therefor in the inner opposed faces 100 of the sections of the connection. An enlarged opening 28 extends centrally through 110

the block and the plate like portion 25 for registration with the opening 18 and the threaded opening formed in the inner section 2. A tightening screw 19 extends through the member 17 and has its inner end threaded into a suitable opening 20 provided therefor in the intermediate portion 4 of the section 2. The construction of the wire securing member is more clearly illustrated in Figure 4 of the drawing. The detachable connection 1 is adapted to be supported in a rigid position adjacent the chimney through the medium of a bracket 21. This bracket comprises the complementary sections 22 and 23 which are detachably secured together by a tongue and slot connection 29 at one end and by a screw 30 at the other end. The bracket is secured on the outside of the chimney so that the inner section will be disposed between the chimney and the inner section of the detachable connection embodying my invention, and the outer section of this bracket encircles the upper outer section of the connection as clearly illustrated in Figure 1. This bracket is adapted to be supported on the chimney in any appropriate manner.

It will thus be seen from the foregoing description, that detachable connecting means has been provided for use in connection with the wires or cables of the lightning arrester system embodied in my copending application whereby the several wires or cables may be readily connected or disconnected without the loss of any considerable length of time or labor. Furthermore, the provision of connecting means of the above mentioned character, will obviate the necessity of having to splice the wires or otherwise provide a permanent connection therebetween. The simplicity in which my various detachable connections are constructed will enable the same to be readily and easily adjusted and furthermore will prevent any

possibility of the displacement of the wires or cables therefrom.

While I have shown the preferred embodiment of my invention, it is to be understood that various changes in the size, shape and arrangement of parts may be resorted to, without departing from the spirit of the invention and the scope of the appended claims.

Having thus described the invention, what I claim is:—

1. A device of the class described comprising a connection including a pair of complementary sections, said sections being provided with cooperating channels for receiving the end portions of a pair of cables, the intermediate portion of one of said sections being provided with an opening which communicates with the channels formed in said sections, a member adapted to be disposed within the opening for securing the free ends of the cables in said connection, and means for detachably securing the sections together.

2. A device of the class described comprising a connection including a pair of complementary sections, said sections being provided with cooperating channels adapted to receive the end portions of a pair of cables, the intermediate portion of one of said sections being provided with an opening which communicates with the channels formed in said section, a block adapted to be secured in said opening, said block being provided with channels adapted for cooperation with the adjacent portion of the channels in the other sections for securing the free ends of the cables in said sections, and means for detachably securing said complementary sections together.

In testimony whereof I affix my signature.

HENRY HEESE.
